ALICE E. CORBITT, OF WAVERLY, WEST VIRGINIA, ASSIGNOR OF ONE-HALF TO
CLAUSON P. CORBITT, OF WAVERLY, WEST VIRGINIA.

DINNER-PAIL.

1,232,227.

Specification of Letters Patent.

Patented July 3, 1917.

Application filed July 21, 1916. Serial No. 110,588.

To all whom it may concern:

Be it known that I, ALICE E. CORBITT, a citizen of the United States, residing at Waverly, in the county of Wood and State 5 of West Virginia, have invented new and useful Improvements in Dinner Pails, of which the following is a specification.

This invention relates to improvements in workmen's dinner pails, the object of the 10 invention being to provide a dinner pail with means whereby the contents of the pail may be readily heated, thus enabling the user of the pail to enjoy hot food, and hot coffee, soup, or the like and at very slight 15 trouble and expense.

The invention consists in the features of construction, combination, and arrangement of devices, hereinafter fully described and claimed.

20 In the accompanying drawings:

Figure 1 is a vertical, longitudinal sectional view of a dinner pail constructed in accordance with my invention.

Fig. 2 is a transverse sectional view of the 25 lower portion of the pail on the line 2—2.

The dinner pail as herein shown is formed with an upright wall 1 preferably oval in contour and beaded at its upper and lower edges and rigidly secured within the same 30 is an imperforate partition 3 extending completely across the body of the pail and dividing it into an upper or food compartment and a lower or heating compartment which is entirely distinct from the food compartment and separated therefrom only by the 35 partition. The latter is relatively so high from the lower end of the wall that there is produced wide chine $\frac{1}{4}$ around the heating compartment, and within this chine is 40 fixed a false bottom 2 having at its center an opening around which is secured a depending screw ring or nipple 5. The heating element is a lamp 6, preferably of that type which consumes alcohol and its body is 45 somewhat smaller than the opening and the nipple and normally closed at its top by a removable cap or snuffer 7. The base plate of said body is carried radially outward beyond its side wall for a short distance, and 50 secured to the edge of said plate and rising therefrom is a screw ring or nipple 8 of a size to engage the threads on the depending screw ring or nipple 5 as shown. The length of the nipple is such that when the outer 55 is run onto the inner until the upper edge

of the outer nipple strikes the false bottom 2, the lamp body stands about half way above and half way below the line of said bottom, and somewhat above the line of the beading at the lower end of the chine 4; but it is obvious that by partly unscrewing the outer nipple from the inner, the lamp could be allowed to descend for quite a little distance before it is detached from the supporting nipple 5 entirely. Thus the connection permits a certain adjustability in the position of the lamp, with the result that its flame may be disposed adjacent to or remote from the partition 3 as desired. When the lamp and its nipple 8 are unscrewed the limit, the nipple is detached from the depending nipple 5 and the lamp entirely removed out of the pail, the latter being held suspended by its handle as will be clear.

The heating chamber is entirely beneath the partition 3, and for supplying air to support combustion I provide a pair of rather large rectangular openings 10 in the flat sides of the wall 1—also I provide 50 a number of smaller or ventilating openings 11 in the chine at the upper part of the heating compartment or just beneath the partition their aggregate size being sufficient to permit the products of combustion 55 to escape without causing the lamp to smoke. The larger openings are also obviously useful for permitting the snuffer plate 7 to be manually inserted and applied to the lamp when the latter is to be extinguished, or for 60 permitting the operator to remove this plate and light the lamp when the lunch is to be heated. Also after the lamp is lighted by properly placing it on the ground the prevailing breeze may be permitted to blow into 65 said openings 10 if it be gentle, or prevented from doing so if a high wind exists and the breeze might blow out the flame.

It will be understood, that coffee, soup, or the like in the pail, may be readily heated 70 to any desired degree by first charging the lamp with a small quantity of wood alcohol or other alcohol, attaching the lamp to the false bottom of the pail and then igniting the same.

The food compartment is provided with a removable pan 13 which is arranged therein at a suitable distance above the partition 3 and the bead 14 at the upper edge of the wall of this pan bears on the bead at the 80

upper edge of the wall of the pail. I also provide a pan 15, which is of less depth than the pan 13 and which is detachably supported with its bead 16 bearing on the bead 14 of said pan 13. Food in the pans 13, 15 may also be heated at the same time as the coffee or soup in the main portion of the pail. The usual ears 17 are attached to the ends of the pail, and a bail or handle 18 10 is pivotally connected to the ears. The cover 20 is detachably fitted around the upper edge of the pail and incloses the upper edges of the pans 13, 15, and is provided at its center with a raised circular portion 21, 15 around which is fitted a detachable cup 22. By the use of my improved dinner pail, a workman may readily provide himself with hot food at very little trouble, in a very short time and at very small expense. In 20 practice, two tablespoons full of wood alcohol suffices for fuel for heating the contents of the pail as thoroughly as may be desired. By the construction above described, it is obvious that the fuel, the products of 25 combustion, and the smell of either if there should be any odor are kept entirely away from the food within the food compartment, while cooking the same or at other times, and the pans or other receptacles therein 30 need not be of any particular contour in order to be useful as cooking utensils, although I prefer to construct them as shown

and described and to use them as herein-before set forth. No flue or other outlet from the heating compartment passes upward above the partition and through or alongside the food compartment, and the latter is entirely uninterrupted and free for the use of a cooking utensil of any shape and size which will pass into it. 35

Having described the invention, what is claimed:

The herein described dinner pail whose body has an upright wall and is internally divided by a transverse imperforate partition into a food compartment above and a heating compartment below said partition, a false bottom across the body beneath said partition and provided with a central opening, a threaded nipple depending from the bottom around said opening, a lamp body smaller than said opening, a threaded nipple rising from its base and of a size to screw around the depending threaded nipple, the walls of the body of the pail having oppositely disposed relatively large openings communicating with the heating compartment and a series of smaller openings communicating therewith at points just beneath said partition; pans for use in the food compartment, and a removable cover. 50

55 In testimony whereof I affix my signature.

ALICE E. CORBITT.
